His Attorney.

UNITED STATES PATENT OFFICE.

WALTER D'ARCY RYAN, OF SCHENECTADY, NEW YORK.

HEADLIGHT.

Application filed September 2, 1924. Serial No. 735,409.

My invention relates to improvements in headlights, and is particularly concerned with improvements in headlights for use on automobiles and other automotive vehicles.

5 The objects of my present invention are:

First, to provide a headlight comprising means for adequately illuminating the roadway in advance of the vehicle carrying the headlight;

10 Second, to provide a headlight comprising means for illuminating the sides of the road immediately adjacent the vehicle, so as to enable the operator to perceive the mile posts and other signs at the sides of the

15 road;

Third, to provide a headlight, such as described, including means for illuminating the sides of the road to the rear of the headlight, so as to illuminate a road into which the

20 operator is turning; and

Fourth, to provide a headlight of the character described that is simple in construction and economical to manufacture.

Other objects of my invention will appear 25 as this description progresses, reference being had to the accompanying drawings, in which

Figure 1 is a side elevation, partially in section; and

30 Figure 2 is a sectional detail on an enlarged scale.

Referring to the drawings, my improved headlight comprises a suitable casing or housing 5, containing and supporting a reflector 6 that may be either ellipsoidal, hyperboloidal or paraboloidal, as may be desired. This reflector is supported by a ring 7 carried by the housing 5. An electric lamp 8 is carried by a suitable socket 9, supported 35 in the bottom of the reflector 6. The filament 10 of the lamp 8 is preferably positioned at or near the focal point of the reflector 6. A bowl-shaped outwardly convex lens 11 is positioned in front of the reflector

40 6 and is provided with a marginal flange 12 that is clamped to the housing 5 by means of suitable clips 13, or in any other desired manner.

The lens 11 is substantially uniform in 45 thickness, except at its margin where it is provided with a plurality of successively inwardly stepped, annular prisms 14 that receive the light reflected from the marginal

portions of the reflector 6 and deflect it laterally and to the rear of the headlight. 55 From an inspection of the drawings it will be seen that one face of each of the prisms 14 is disposed substantially at right angles to the axis of the reflector, whereas the other face is disposed at an acute angle to the axis. 60 It will also be noted that the angle between the two faces of each prism is larger in each succeeding prism. The outer face of the lens, opposite the prisms 14, is stepped, as shown in Figure 2, so as to provide substantially non-deflecting surfaces through which the laterally deflected rays of light may pass.

By the arrangement described above, I provide a headlight in which practically all of the light reflected from the central portion of the reflector is utilized for illuminating the roadway ahead of the vehicle, and the light reflected from the margin of the reflector is used for illuminating those portions of the sides of the road immediately adjacent the vehicle. The directions of the forwardly projected rays and the laterally and rearwardly projecting rays are clearly indicated by the arrows in the drawings.

By placing the annular prisms so as to 75 deflect the rays of light reflected from the marginal portions of the reflector, I eliminate the source of glare in headlights of conventional design and make use of that light that usually produces glare for illuminating 80 the roadway immediately ahead of the vehicle and for illuminating the sides of the road immediately adjacent the vehicle.

While I have described the details of construction of the preferred embodiment of 85 my invention, it is to be clearly understood that my invention is not limited to these details, but is capable of other adaptations and modifications within the scope of 90 the appended claim.

Having thus described my invention, 95 what I claim is:

A headlight comprising a reflector, a source of light in said reflector, and a bowl-shaped lens for said reflector having a plurality of inwardly stepped annular prisms 100 adjacent the margin thereof, said prisms each having one inwardly extending face substantially at right angles to the axis of said reflector and another inwardly extending face at an acute angle to said axis, the 105

angles between said faces increasing from the inner to the outer prism and the greater portion of said lens being substantially non-refractive whereby the greater portion of the beam reflected from said reflector will be projected through said non-refractive portion while the rays reflected from the mar-

ginal surface of said reflector will be intercepted by said prisms and refracted laterally.

10

In witness whereof, I hereunto subscribe my name this 16th day of August, 1924.

WALTER D'ARCY RYAN.
